UNITED STATES PATENT OFFICE.

THADDEUS A. NOLAN, OF CINCINNATI, OHIO.

SIGN-PROJECTION APPARATUS.

Application filed January 24, 1921. Serial No. 439,485.

To all whom it may concern:

Be it known that I, THADDEUS A. NOLAN, a citizen of the United States, residing at Cincinnati, in the county of Hamilton and State of Ohio, have invented a new and useful Improvement in Sign-Projection Apparatus, of which the following is a specification.

An object of my invention is to produce 10 a sign projection apparatus in which the character images are made to appear upon and move across the sight portion of the sign in proper sequence and in uniform regularity.

15 A further object is to produce an improved sign of the image projection type in which the characters thereof are placed upon the character-bearing element in a manner such that a great length of legend or other display matter may be projected 20 from a relatively short length of character-bearing element.

25 A further object is to produce a sign of the image projection type in which means are provided for projecting character images individually and consecutively from a character-bearing element containing more than one row of characters at any point thereof taken transversely of its 30 length.

35 A further object is to produce apparatus for the projection of character images from a character-bearing element of the type and in the manner set forth in the preceding objects.

These and other objects are attained in the sign described in the following specification and illustrated in the accompanying drawing in which:

40 Fig. 1 is a side elevation of a sign projection apparatus embodying my invention, the character-bearing element of the apparatus being broken away and the lamp house door being shown partly open to more 45 clearly illustrate other details of the apparatus.

Fig. 2 is a front elevation of the apparatus as shown in Fig. 1.

50 Fig. 3 is a plan view of the apparatus shown in Figs. 1 and 2.

Fig. 4 is a transverse sectional end elevation taken on the line 4-4 of Fig. 1.

Fig. 5 is a fragmental transverse sectional elevation taken on the broken section line 5-5 of Fig. 4. 55

Fig. 6 is a transverse sectional plan view taken on the line 6-6 of Fig. 4.

Fig. 7 is a somewhat diagrammatic elevation of the character-bearing element of the apparatus embodying my invention. 60

Fig. 8 is a fragmental and somewhat diagrammatic detail view of a slight modification of my apparatus.

My invention consists in providing a character-bearing element and especially designed mechanism to be used in connection therewith, whereby a great length of reading or display matter may be had from a relatively short and easily handled character-bearing element such as disclosed in 70 Figs. 1, 2, 3 and 7. 65

In describing my invention I will first describe the character-bearing element. The reading or display matter is placed upon the character-bearing element in a spiral line, 75 the element preferably being of a flexible material such as paper or other material like the film which is found in motion picture films, but is made relatively short and endless. In Fig. 7 I have shown the character-bearing element 8 in elevation, with the characters diagrammatically shown by lines 9 to illustrate the spiral placing of the display matter thereon. The character-bearing element is normally in ring or band 80 form and the lines as disclosed in Fig. 7 will form one continuous line spirally arranged upon the band in convolutions. 85

The apparatus shown for moving the band shown in Fig. 7 and for projecting therefrom images of the characters which are punched, stamped, stenciled or otherwise placed thereon, has a base 10 on which is mounted at one end a lamp house 11, with film moving mechanism 12 adjacent thereto. 90 In the base an electric cable 13 enters to supply current to the lamp 14 within the lamp house as well as to the motor 15 which drives the film-moving mechanism a regulator or governor 16 being provided for increasing 100

or decreasing the speed of the motor. Driven directly by the motor shaft 17 is a worm 18, the shaft having bearing in two journals 19 and 20. This worm meshes with a gear 21 which in turn drives a shaft 22 upon which a worm 23 and two bevel gears 24 and 25 are secured. This shaft 22 is journalled at its ends in bearings 26 and 27. The worm 23 meshes with a gear 28 which drives a shaft 29 upon which a cam 30 is mounted for being driven thereby.

A frame 31 extends upwardly from the base and is provided with an opening 32 located between two vertical shafts 33 and 34 having bearing in a forward extension 35 at the top of the frame above opening 32 and in a similar extension 36 below opening 32. A bevel gear 37 which meshes with gear 24 is secured to the lower end of shaft 33 and a duplicate gear 38 is secured to the lower end of shaft 34. Each shaft 33 and 34 is provided with a knob 39 at its upper end and a groove 40 directly beneath the knob, into which the end 41 of a set screw 42 may be brought to hold the shaft elevated as shown at the left of Fig. 4 so that bevel gears 24 and 37 or 25 and 38 may be held from engagement with each other, or allowed to drop to engage each other, the purpose of which will be hereinafter explained.

Slidingly mounted upon the shafts 33 and 34 is a frame 43 and carried by the frame, when it is moved upon the shafts, are sprockets 48 and 49 which are splined upon the shafts and which are provided with teeth 50 which engage the sprocket holes 51 of the character-bearing element shown in Fig. 7, and cause it to be moved as will be herein-after set forth. To cause the frame 43 to reciprocate upon the shafts I provide an arm 45 carrying a roller 44 which rides upon the surface of cam 30 which is designed to maintain the line of characters on the character-bearing element in constant registration with an aperture 71 which is hereinafter described. Cooperating with the sprockets are rollers 52 and 53 which are rotatively mounted in the ends of lugs 54 on a relatively light auxiliary frame 55 which is movable with relation to frame 43, but which is connected for movement therewith by means of a pair of rods 56 and 57 which are secured in auxiliary frame 55, but which slide in frame 43. The ends of rods 56 and 57 extend to the rear of frame 43 and have mounted upon them springs 58 and 59 which bear against washers 60 and 61 on the rods. These springs draw auxiliary frame 55 toward frame 43 and hold rollers 52 and 53 toward sprockets 48 and 49 so that the character-bearing element is held in proper relation to the sprockets. Between frame 43 and auxiliary frame 55 I have located a primary aperture plate 62 which is held against extensions 35 and 36 of frame 31 by screws

63 and 64 located in slots in the aperture plate. About centrally between extensions 35 and 36 and in axial alignment with the condenser tube 65 of the lamp house and lens tube 66 I have located an aperture 67 in the plate, this aperture being somewhat wider than the height of the characters on the character-bearing element and located in alignment with a central opening 68 in the auxiliary frame 55. In front of plate 62 a secondary aperture plate 69 is located, this plate being spaced from plate 62 by a block 70 to afford a space in which the character-bearing element may travel to and from the sprockets 48 and 49.

Secondary aperture plate 69 is provided with an aperture 71 the width of which is the height of the characters on the character-bearing element 8. In the upper end of plate 62, which extends above frame extension 35, I have provided a pin 72 which extends rearwardly into a slot 73 of an adjustment screw 74 which extends above extension 35 for purposes of adjustment of the aperture plates to bring aperture 71 into alignment with the line of characters on the character bearing element 8 passing between the apertures 67 and 71 over sprockets 48 and 49. On the front of auxiliary frame 55 I have secured a lug 75 beneath which the bent crank portion 76 of a rod 77 is located. Rod 77 extends across the auxiliary frame 55 and is journalled in bearings 78 and 79 thereon, the ends 80 and 81 being turned for use as lifting handles for rocking the rod to cause its crank portion 76 to pull auxiliary frame 55 away from the frame 43 against the pressure of springs 58 and 59 so that the character-bearing element may be placed in position when the rollers and the sprockets are thus separated. Pressing down on the handles causes the auxiliary frame to be released so that the rollers will hold the character-bearing element in position on the sprockets.

The lens tube 66 as well as the lamp house 11 are shown mounted on rods 82 and 83 located in extensions 36 of the stationary frame 31, the lens tube holder 84 being adjustable on the rods and the tube being in turn adjustable within the holder for purposes of proper focusing.

I have provided an adjustment device for the governor 16, consisting of a disc 85 attached to the governor weights, a lever 86 which is pivoted between its ends on a bearing 87 and has one end cushioned to bear against the disc 85 with the other end held by a spring 88 against a cam 89 secured to the lower end of a vertical shaft 90 upon the upper end of which an adjustment knob 91 is located.

In order to bring the image which is projected from the lens tube, into proper elevation on the sight portion of the sign, which

may be the screen, wall or other back ground against which the image is thrown, I have provided an adjustable foot 92 located in a bearing 93 at the forward end of the base 10 and having a thumb screw 94 for holding it in adjusted positions. By this means the entire apparatus may be tipped back upon its stationary feet 95 and 96 to bring the image into proper position upon the screen 10 or sight portion.

An additional feature of my apparatus lies in the provision of an automatic circuit breaker by means of which the apparatus may be stopped upon the completion of the 15 display matter upon the character-bearing element. This automatic circuit breaker consists of a pivoted switch lever 97 and contacts 98 which are held together normally by a spring 99, but which may be 20 moved apart when a bar 100 engages a rearwardly extending finger 101 of the switch lever, as shown in Fig. 1. Bar 100 is frictionally pivoted at a point 102 on the side of the sliding frame 43 and is adapted to 25 be moved to the full line position shown, when it is desired to have the mechanism stop upon completion of the showing of the display matter, or it may be swung aside to the dotted line position, in which it will 30 stay, when it is desired to allow the mechanism to continuous operation for an indefinite period with repeated display of the subject matter of the character-bearing element.

In the operation of my invention the apparatus is started with the sliding frame riding upon the lowest portion of the cam, thus placing the character-bearing element in position to have the beginning of the legend 40 thereof appear through aperture 71. To facilitate the alignment of the aperture plates with the characters of the character-bearing element, the adjustment screw is turned to raise or lower the plates. The speed of operation 45 of the mechanism, the spacing between the convolutions of characters on the character-bearing element, and the rate of lift of the cam being proportioned to one another, the successive characters in the spiral line will 50 always appear in register with the aperture 71 and the speed may be varied to suit the speed at which the sign can be read easily. When the end of the reading matter is reached, the highest point of the cam will 55 pass beyond the roller 44 of the sliding frame, whereupon the frame will drop, thus bringing the display matter upon the band to the point of beginning, it having been proportioned to end and begin at this period 60 of the operation. In order that the frame 43 may not drop with a jar, the arm 45 may be offset slightly from the center line of the cam so that the roller 44 will ride down the straight side of the cam instead of dropping 65 from the end of the curved surface directly

to the point of beginning thereof. To change from one character-bearing element to another, the handles 80 and 81 are operated to cause the rollers 52 and 53 to release the element when it may be removed and a 70 new one put in its place, whereupon the handles being released, the apparatus may be started, the image projection in each case taking place through aperture 71, the image of the new legend appearing in motion upon 75 the sight portion of the sign as previously described.

However to facilitate the changing of one character-bearing element to another having a different legend, after the movable frame 80 has dropped and the circuit breaker has stopped the mechanism, I have provided on either the plate 69 or frame 55 or both, an element centering line or arrow 103 which, when a cooperating line or arrow 104 on the 85 character-bearing element is brought into registration therewith, will place the element in proper position for beginning the display of its legend through aperture 71.

The drawings show the apparatus arranged to display the subject matter of the element through a translucent sight portion such as ground glass, prepared or thin paper or cloth, etc., instead of upon an opaque surface. Should it be desired to display 90 the subject matter on any opaque surface it is but necessary to lift upon knob 39 to remove gear 38 from gear 25 and to secure it in gear disengaging position by bringing the end 41 of set screw 42 into 100 groove 40 of shaft 34, at the same time allowing gear 37 to mesh with gear 24 by removing end 41 of screw 42 from groove 40 of shaft 33, which converts sprocket 48 into the driver instead of sprocket 49 105 which is now the idler. The character-bearing element, which is merely a relatively short band, is now turned inside out and the band is turned over to bring the beginning of the legend in proper position at the top 110 edge thereof, as previously. This causes the characters to be reversed from their previous position and to be presented to the apparatus side of the sight portion, in correct order and moving correctly from the viewer's 115 side of the sight portion. The projection of the character images therefore will appear in correct order and move in proper sequence across the sight portion.

The style of projection just described, in 120 which both the viewer and the apparatus are on the same side of the sight portion, is of value in the usual motion picture theatre, in projecting against walls of buildings, sign boards, and the like; while the reverse 125 method first described is particularly desirable in show windows and in similar cases where reverse side projection would have to be used.

Although I have described my invention 130

as being embodied in the apparatus illustrated, various modifications and deviations therefrom may be made without departing from the spirit and scope of my invention as set forth in the following claims.

What I claim is:

1. In combination in a sign projection apparatus, an endless, flexible and reversible character-bearing element with the characters arranged thereon in a spiral line having a series of convolutions of characters, an aperture plate, mechanism for moving the element to bring the characters across the aperture of the aperture plate, in registration therewith and in proper sequence, and an automatic stop having manually operable means for placing it in and out of operative relation with the mechanism, whereby the mechanism may be stopped automatically upon completion of the display of the characters on the character-bearing element.

2. A sign projection apparatus comprising a character-bearing element with the characters arranged thereon in a spiral line having a series of convolutions, an aperture plate, mechanism for moving the element longitudinally across the aperture of the aperture plate, separate mechanism for moving the element transversely to bring the characters in a spiral line consecutively in registration with the aperture, an automatic stop, and means adapted to coordinate the operations of the first mentioned mechanism, the second mentioned mechanism, and the stop, whereby the stop will stop the mechanisms upon completion of the movement of the characters across the aperture.

3. In a sign projection apparatus the combination of an image projection device, a band-like character-bearing element having the characters thereof arranged in a spiral line having convolutions, mechanism for moving the character-bearing element longitudinally and transversely in operative relation to the projection device, manually operable means for reversing the mechanism, means for driving the mechanism, and a manually and automatically operable stop adapted to stop the means upon completion of the display of images projected from the characters on the character-bearing element.

4. In a sign projection apparatus the combination of a character-bearing element, and a mechanism for moving the character-bearing element, said element having a series of lines of characters thereon arranged in substantially spiral formation, said mechanism consisting of a stationary frame, a movable frame reciprocally mounted on the stationary frame, element propelling means on the movable frame adapted to

propel the element longitudinally, continuously and uniformly, an aperture plate, and means for regularly interrupting the movement of the movable frame and simultaneously with the longitudinal movement of the element propelling means, whereby the element will be moved transversely relatively to the aperture plate and the characters will be presented to the aperture of the aperture plate in registration therewith and in proper sequence.

5. In a sign a character bearing element having the characters of a legend or other display matter arranged thereon in substantially a series of lines extending longitudinally of the element, and means for operating the character bearing element, consisting of a relatively stationary frame, a relatively movable frame, element moving means on the movable frame, movable frame moving means on the stationary frame, and driving mechanism adapted to coordinate the operation of the frame and element moving means and to impart to both continuous uniform movements in directions transversely opposed to each other, said frame moving means having a cam adapted to maintain successive characters of the character bearing element in display alignment with a sign sight portion during movement of the element.

6. A sign comprising an endless character bearing element, an aperture plate, mechanism for mounting and moving the character bearing element longitudinally thereof with reference to the aperture plate, separate mechanism for mounting and moving the element transversely of the aperture plate simultaneously with the longitudinal movement of the element, driving mechanism for the longitudinal and transverse movement mechanisms connected therewith for the coordinate operation thereof, and a reversing device for the longitudinal movement mechanism.

7. In a sign the combination of a flexible and reversible character bearing element, mechanism for mounting and moving the character bearing element longitudinally thereof with reference to the aperture plate, separate mechanism for mounting and for moving the element transversely of the aperture plate simultaneously with the longitudinal movement of the element, driving mechanism for the longitudinal and transverse movement mechanisms connected therewith for coordinate operation thereof, and means for reversing the longitudinal motion mechanism to drive the element in a reverse longitudinal direction when the element is reversed.

THADDEUS A. NOLAN.
